UNITED STATES PATENT OFFICE.

LOUIS F. HAGEMANN, OF NIAGARA FALLS, NEW YORK, ASSIGNOR TO AMERICAN SALES BOOK COMPANY, LIMITED, OF TORONTO, ONTARIO, CANADA, A CORPORATION OF ONTARIO.

AUTOGRAPHIC REGISTER.

Application filed July 17, 1917. Serial No. 181,019.

To all whom it may concern:

Be it known that I, LOUIS F. HAGEMANN, a citizen of the United States, residing at Niagara Falls, in the county of Niagara and

5 State of New York, have invented certain new and useful Improvements in Autographic Registers, of which the following is a full, clear, and exact description, such as will enable others skilled in the art to which

10 it appertains to make and use the same.

This invention relates to autographic registers, and with regard to its more specific features to autographic registers adapted for use with a plurality of webs.

15 An object of this invention is to provide a device of the character described adapted to feed a web over a support a predetermined amount, the amount being determined by the construction of the web.

20 A further object of the invention is to provide a device of the character described for feeding a plurality of webs over a support capable of aligning said webs with each other.

25 A further object of the invention is to provide a register of the character described capable of feeding a plurality of webs over a support adapted to stop the feeding of one or more of said webs independently of 30 the others as it reaches predetermined position.

Another object of this invention is to provide a device of the character described with an improved means for maintaining a tension upon the rolls.

35 The invention accordingly consists in the features of construction, combinations of elements and arrangement of parts which will be exemplified in the construction hereinafter set forth, and the scope of the application of which will be indicated in the following claims.

In the accompanying drawings attached to this specification and forming a part 45 hereof, in which similar reference characters refer to similar parts throughout the several views,—

Figure 1 is a plan view of a register embodying my invention;

50 Fig. 2 is a side elevation, taken partly in section;

Fig. 3 is an end elevation, taken partly in section;

Fig. 4 is a detail of the web feeding means;

Fig. 5 is a view of the web tensioning device;

Figs. 6, 7 and 8 are diagrammatic perspectives showing the operation of the device with webs having sales slips of different lengths.

The numeral 1 indicates a frame comprising a base 2 and side plates 3 and 4 and top plates 5 and 6, the former serving as a support for the slips on which the inscription is to be made, and the latter serving as a protection for the portion of the machine not covered by the support 5. Suitable tie rods, as 7 and 8, may extend between the side plates 3 to hold the side plates 70 in position, and on one of these, as the rod 8, the top plate 6 may be pivoted so as to enable it to be swung up free from the machine.

Means are provided for supporting a plurality of rolls of web between the side plates 3 and 4, and with regard to the broader aspects of this invention any means may be employed for this purpose. Certain specific advantages are obtained, however, by the use of the particular mechanism herein illustrated, and this particular mechanism and the use of it in an autographic register are within the scope of this invention.

Mounted upon the inner side of each of the side plates 3 and 4 are a plurality of supporting lugs 11 having a substantially vertical portion 12 and an inclined portion 13. The lugs 11 on the side plate 4 will be of the same shape and in the same corresponding position as those on the side plate 3 whereby there is formed between the side plates by means of these lugs a pocket in which the roll of web may be inserted.

It is within the broad scope of this invention that any number of rolls of web may be used, but the feeding mechanism hereinafter described is particularly designed, and certain specific advantages are obtained, when it is used with a plurality 100 of webs, especially with four or more. In the embodiment of the invention illustrated in the drawing provision is made for the use of four webs. There will thus be four supporting lugs on each of the side plates 3 and 4, and they may conveniently be so

spaced that the vertical portion of one supporting lug will serve to keep the roll in place upon the next supporting lug in advance of it, except for the last supporting lug, which, by reason of having no further supporting lugs to retain its roll in place, may be supplemented by stop lugs 15.

Extending between the side plates 3 and 4, preferably in position to have their upper 10 surface flush with the plane of the support 5, are a plurality of guide rollers 16, and these rollers will be at that end of the frame away from which the inclined portions 13 of the supporting lugs 11 slope, so that as a roll of 15 web is placed upon the inclined portion of the supporting lugs and the end of the web is carried over the guide rollers, as shown in Fig. 2, the tension on the web will tend to cause the roll to rise on the inclined portion 13. Suitable anti-friction rollers 17 may if desired be placed opposite the vertical portion 12 of the supporting lugs 11, against which the roll of web may bear when the web is subjected to tension and upon the 20 inclined portion, near the vertical portion to support the roll.

Means are provided for feeding the webs over the support 5, and this means may be such as to align the webs relative to each 30 other and relative to the machine. This comprises means for feeding each web independently of the other webs a predetermined amount measured by the web itself, that is, the webs and feeding means are so arranged 35 that each web, as it reaches predetermined position, will automatically cease to co-operate with the feeding means in such manner as to be fed further. To this end the web may be provided with a series of prepared 40 portions of such a character that when a prepared portion comes opposite some predetermined portion of the feeding means, the feeding of the web by the feeding means will cease. Within the broad scope of this invention any feeding means may be employed 45 which is adapted to co-operate with the web to feed the same until a prepared portion of the web comes opposite some predetermined point, whereby the distance the web is fed is determined by the character of the web; and, 50 within the capacity of the machine, independently of the feeding mechanism. To accomplish in a practical manner this end the webs may be provided each with a series 55 of feeding sections spaced apart from each other by a series of non-feeding sections, that is a series of sections so arranged as to co-operate with the primary feeding means to cause the feeding of the web, and sep- 60 arated from each other by sections which do not actively co-operate with the primary feeding means to feed the web.

In the embodiment illustrated each of the webs is provided with a series of apertures or 65 perforations bearing a predetermined rela-

tion to the sales slips or other indicia that may be printed on the web, and the feeding means is arranged to feed the web until such time as the perforations are opposite a predetermined point, whereupon such web 70 ceases actively to co-operate with the feeding means, even though movement of the feeding means be continued. Thus the strip of material between the perforations will act as a feeding section of the web and the perforations will serve as non-feeding sections. 75 It will be understood that the non-feeding sections may be provided upon the web otherwise than by removing a portion of the web, as for example by any means which 80 will cause the web not to co-operate with the primary feeding means.

As illustrated, the primary feeding means comprises rotary means for engaging the webs, which means are in line with the perforations in the webs, and are of less width than the perforations, whereby when the feeding means comes opposite the perforations in the web, that web will no longer engage the feeding means to feed. Other superimposed webs, however, if they should not happen to be in longitudinal alignment with the web the perforations of which first come opposite the feeding means, will continue to be fed by the feeding means, which 90 is enabled to engage them through the perforations in the first aligned web.

In the drawings the numeral 20 indicates a shaft journaled in the side plates 3 and 4 having at its outer end convenient means 100 for rotating the same, as for example an operating handle 21. Mounted upon the shaft 20 in lateral alignment with the perforations in the webs with which the device is intended to be used are drive rolls, feed rollers, 105 or disks 22 which will preferably have a circumference slightly greater in length than the longest sales slip which the machine is intended to feed, and will be of a width, or thickness less than the lateral dimension of 110 the perforations in the web. Attached to the side plates 3 and 4 are upstanding brackets 24 in which is journaled a shaft 25 carrying members, as rollers 26 opposite to, and adapted to co-operate with the feeding rollers, or disks 22, and for the purpose of maintaining the rollers 26 normally in engagement with the disks the journals of the shaft 25 in the brackets 24 may be urged downwardly by springs 27 in sockets 28 in the 115 brackets 24, the springs 27 being retained in place by screws 29. Thus the members 26 serve as pressure rolls.

In order to cause rotation of the rollers 26 and of the disks 22 in unison, that is, with 120 the same peripheral speed, a pinion 30 may be placed upon the shaft 25 adapted to mesh with a gear 31 on the shaft 20.

With the above described construction a rotation of the shaft 20 would cause the 130

feeding of a web situated between the disks 22 and the rollers 26 until such time as the perforations in the web come opposite the point of contact between the roller and the disk, whereupon the feeding forward of the web would stop. In order, therefore, to provide for the moving of the web forward to start the feeding of the next sales slip, means are provided for temporarily engaging the web and feeding the same until the perforation has passed the point of contact between the roller and the disk. To this end there is provided means for engaging the web elsewhere than at the perforation, as for example, at the side of the perforation. As illustrated, there is provided upon the side of the disk 22 a block 34 surfaces of which are so situated as to come into engagement with the roller 26 once during each revolution of the shaft 20, and this block 34, as well as the rollers 26, are of sufficient width or are so situated as to bear upon the web at the side of the perforations.

In order to stop the rotation of the shaft 20 just after the block 34 comes into engagement with the roller 26, a stop mechanism is provided. As illustrated, the grip 36 on the handle 21 is mounted for longitudinal movement on the handle and is held inwardly by a spring 37 and carries at its inner end a pin 38 adapted to engage with any suitable portion of the framework, as for example with one of the brackets 24.

In order to assist in the aligning of the webs where a large number of webs, as for example, four, are employed, pins 39 may be placed upon the disks 22 in position to extend upwardly through the perforations in the web, and these pins will be of sufficient length to bear upwardly against the rollers 26 and separate them from the disks. These pins will preferably be situated on the disks in such position that they will be in engagement with the rollers 26 when the pin 38 has stopped the rotation of the handle. The pins 39 are preferably situated between the advance and rear sides of the blocks 34 whereby, as the disks 22 are rotated, the advance edge of the blocks 34 will engage the web to move it a slight distance forward just before the pins intervene between the disks 22 and the rollers 26 to separate the latter. By this construction the advance edge of the perforation in the web will be moved beyond the point which the pins will occupy when the rollers are separated. Thus the separation of the rollers will permit the tension on the web to draw the web backwardly against the pins, causing each web independently to snap back into position against the pins. Thus the pins 39 insure the more accurate aligning or adjusting of the webs and the printed forms thereon and assist in the operation,

when a large number of webs are to be fed.

In order to permit free access to the interior of the machine, the support 5 may be pivoted to the side plates 3 and 4, as by being journaled upon the shaft 20.

For the purpose of enabling the projecting ends of the webs to be torn from the web, a suitable tearing bar, as 42, may be provided.

The operation of this device is as follows: 75 Rolls of web may be inserted in the frame of the machine by throwing back the support 5 and the top plate 6 and laying rolls upon the supporting lugs 11. The free end of the web will then be carried over one of the guide rollers 16 and up over the support 5 and caused to pass between the disks 22 and the rollers 26. It will be understood that one guide roller will be provided for each web. The rolls of web will preferably be placed in such position that the free end of the web will pull off the top of the roll. The top plate 6 may now be thrown over the lower portion of the free end of the web. Each of the webs in turn 80 is thus carried up and over the support, suitable carbon being placed between them for the purpose of making a manifold copy.

It will be convenient to start the machine with the webs substantially in alignment with each other, but the machine is capable of producing this alignment even if this is not done, and if the webs are not in alignment the operating handle 21 will 95 be turned until such alignment is produced. The machine is now ready to have any inscription which may be desired made upon the first slip on the web.

To operate the machine, the grip 36 on the operating handle 21 is moved outwardly to free the pin 38 from the bracket 24, and the shaft 20 is turned through one complete revolution until the pin 38 again comes in contact with the bracket 24. During this revolution the feeding of all four webs will continue due to the co-operation between the disks 22 and the rollers 26 until the perforations in any web reach the point of contact between the rollers and the disk. Thereupon there will be no engagement with that web to feed the same, and the feeding thereof will be prevented by the tension on the web. Any other web, however, the perforations of which have not yet reached the point of contact between the disk and the roller, will continue to be fed until its perforations in turn reach such point of contact.

Thus each web in turn will be fed the 125 distance of the sales slip on the end of the web, and this is true regardless of whether the sales slips on the different webs are of the same length or of different lengths, and regardless of whether the successive sales 130

slips on the same web are of the same length:

When the perforations in all of the webs have come opposite the point of contact between the disk 22 and the roller 26, no further feeding of any of the webs will take place until near the completion of the rotation of the shaft 20, when the advance edge of the block 34 comes in contact with the web 10 to cause a slight further feeding. On the completion of the rotation of the shaft 20 the pins 39, by raising the rollers 26 out of engagement with the webs, effect relaxation of the pressure between the rolls 22 and 26 15 and by themselves entering the perforations in the webs, will permit the webs separately to move backwardly with a retrograde motion until the edge of the perforation comes in contact with the pins, thus increasing the 20 accuracy of the alignment of the webs. After this backward movement, slight further rotation of the handle causes the pins to advance the webs slightly by engagement with the edges of the apertures or perforations in the webs, the pressure between the 25 rolls 22 and 26 being relaxed during this slight interval.

When the handle 21 is again turned, the pins 39 pass out of engagement with the 30 rolls 26 and the webs are gripped at the side of the perforations by the block 34.

The embodiment of the invention illustrated in Figs. 1 and 4 is provided with pins 39, and the machine is preferably so 35 equipped when a large number of webs are to be fed. Ordinarily, however, and particularly when a small number of webs are fed, the operation will be found satisfactory without the pins 39, and the use of the device without these pins is within the purview of this invention.

Figs. 6, 7 and 8 show diagrammatically the use of this register with a plurality of webs each having sales slips of a different 45 length. It will be understood that any one of these webs may have the shorter slips thereon, and in the drawing the upper is shown as having the shortest, and the lower web as having the longest slips.

In Fig. 6 is shown the feeding operation before any of the three webs has reached its predetermined position. In this figure the numerals 45, 46 and 47 indicate the perforations in the top, intermediate and bottom webs respectively at the end of the web, and the numerals 45^a, 46^a and 47^a represent the next set of perforations in each of the webs respectively. As shown in Fig. 6, the perforations 45, 46 and 47 are in alignment, but by reason of the fact that the sales slips on the different webs are of different lengths, the perforations 45^a, 46^a and 47^a are spaced from each other.

At the start of the feeding operation, with 65 the webs in alignment, as shown in Fig. 6,

all three webs will be fed in unison until such time as the perforations 45^a come opposite the point of contact between the disks 22 and the rollers 26. At this point in the feeding operation the top web will cease to move and the lower two webs will continue to be fed in unison as shown in Fig. 7. This feeding of the lower two webs with the upper web stationary until the perforation 46^a has come into alignment with the perforation 45^a, whereupon the intermediate web will remain stationary. Thereafter on further turning of the disks 22 the lower web alone will be fed, the upper two remaining stationary until the perforation 47^a has come 75 into alignment with the perforations 45^a and 46^a. Thus each web has been fed a distance equal to the length of the sales slip on that web independently of the amount of movement of the feeding mechanism and independently of the distance which the other webs are fed.

Thus by the above described construction are accomplished, among others, the objects herein set forth.

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

It is also to be understood that the language used in the following claims is intended to cover all of the generic and specific features of the invention herein described, and all statements of the scope of the invention which, as a matter of language, might be said to fall therebetween.

Having described my invention, what I claim as new and desire to secure by Letters Patent is:

1. A device of the character described adapted for use with a web provided with longitudinally spaced perforations, comprising, in combination, a support for a web, means for feeding said web over said support comprising a rotary disk adapted to engage said web in longitudinal alignment with the perforations, means adapted to hold said web in engagement with said rotary disk, and means for separating said rotary disk and said last-mentioned means at a predetermined instant in the feeding operation.

2. A device of the character described adapted for use with a web provided with longitudinally spaced perforations, comprising, in combination, a support for a web, means for feeding said web over said support comprising a member adapted to engage said web in longitudinal alignment with the perforations, means adapted to hold said

web in engagement with said member, and means carried by said member for separating said member and said last-mentioned means at a predetermined instant in the feeding operation.

3. A device of the character described adapted for use with a web provided with longitudinally spaced perforations, comprising, in combination, a support for a web, means for feeding said web over said support comprising a member adapted to engage said web in longitudinal alignment with the perforations, means adapted to hold said web in engagement with said member, and means carried by said member adapted to extend through said web at the perforations and bear against said last-mentioned means to separate said member and said means.

10 4. A device of the character described, comprising, in combination, a support for webs, means for feeding and approximately aligning a plurality of webs relative to said support, means for completing the alignment of the webs, comprising means for feeding the approximately aligned webs forward a slight distance, means to free the webs from restraint against retrograde motion, and means to stop retrograde motion of the webs to retain the webs in predetermined position.

5. A device of the character described adapted for use with webs having longitudinally spaced perforations, comprising, in combination, a support for webs, means for feeding webs relative to said support comprising means for engaging said web in alignment with the perforations whereby said web will be fed a distance equal to the distance between perforations, means to engage said web at the side of said perforations to feed the web slightly forward after the webs have been substantially aligned, means for releasing the web from the feeding means after said slight forward feed, and means for engaging the edge of the perforations to restrain the retrograde motion of the web to hold the webs in alignment.

50 6. In a device of the character described, in combination, a feed roller and cooperative member adapted to grip and feed a web, and means adapted to separate said roller and member and effect the alignment of the web including a web aligning pin carried by said roller.

60 7. In an autographic register, in combination, a roll feed for duplicate paper strips, means for positively engaging the paper strips at the line of feed to shift them into alignment with each other for each feeding operation, and means for releasing the strips from frictional feeding contact of the roll during shifting.

65 8. In a device of the character described,

in combination, a feed roller and cooperative member adapted to grip and feed a web, and a web aligning pin carried by said roller and disposed to separate said roller and member at a predetermined point in the rotation of said roller.

9. In a device of the character described, in combination, a feed roller and cooperative member adapted to grip and feed a web, the gripping surface of said roller being of a width to enter apertures in the web and thereby cause cessation of feed, and a starting feed surface fixed to said roller to effect resumption of feed, and a web aligning pin carried by said roller and adapted to separate said roller and member at a predetermined point in the rotation of the roller.

10. In a device of the character described, in combination, a feed roller and cooperative member adapted to grip and feed a web, the gripping surface of said roller being of a width to enter apertures in the web and thereby cause cessation of feed, a starting feed surface fixed to said roller to effect resumption of feed, and a web aligning pin carried by said roller and adapted to enter said apertures and separate said roller and member at a predetermined point in the rotation of the roller.

11. In a device of the character described, in combination, a feed roller and cooperative member adapted to grip and feed a web, the gripping surface of said roller being of a width to enter apertures in the web and thereby cause cessation of feed, a starting feed surface fixed to said roller to effect resumption of feed, and a web aligning pin carried by said roller and adapted to enter said apertures and separate said roller and member at a predetermined point in the rotation of the roller, said starting surface being partly in advance of said pin.

12. In a device of the character described, in combination, a feed roller and cooperative member adapted to grip and feed a web, the gripping surface of said roller being of a width to enter apertures in the web and thereby cause cessation of feed, a starting feed surface fixed to said roller to effect resumption of feed, and a web aligning pin carried by said roller and adapted to enter said apertures and separate said roller and member at a predetermined point in the rotation of the roller, said starting surface being partly in advance of said pin and partly in rear of said pin.

13. In a device of the character described, in combination, a feed roller and cooperative member adapted to grip and feed a web, the peripheral length of said roller being slightly greater than the length of a single sales slip of said web, a handle for operating said roller, a stop to arrest the roller upon a single rotation thereof,

- and a web aligning pin movable to separate said roller and member, said pin being arranged to separate said roller and member upon the arrest of said roller by said stop.
5. 14. In a device of the character described, in combination, a pair of intergeared cooperative feed rollers, the peripheral length of one of said rollers being slightly greater than the length of a single sales slip of said 10 web, a handle for operating said rollers, a stop to arrest feed by said rollers upon rotation sufficient to feed a length of web approximately equal to that of a single sales slip, a web aligning pin carried by one of 15 said rollers into and out of apertures in the web and into and out of contact with the other roller to raise and lower the latter, said pin being disposed to space said rollers apart at the time of arrest of their rotation by said 20 stop.
15. In a device of the character described, in combination, a pair of rollers adapted to feed a web, one of said rollers being of a width to enter apertures in said web and 25 cause cessation of feed, a handle for operating said rollers, a stop to arrest feed by said rollers upon rotation sufficient to feed a pre-determined length of web, and a movable web aligning pin adapted to separate said 30 feed rollers upon arrest of said feed by said stop.
16. In a device of the character described, in combination, a pair of rollers adapted to feed a web, one of said rollers being of a width to enter apertures in said web and 35 cause cessation of feed, a handle for operating said rollers, a stop to arrest feed by said rollers upon rotation sufficient to feed a pre-determined length of web, a movable web 40 aligning pin adapted to separate said feed rollers upon arrest of said feed by said stop, and rotatable web gripping surfaces, one in advance and one in rear of said pin, adapted to grip said web at the side of the 45 apertures therein.
17. In a device of the character described, in combination, a pair of rollers adapted to feed a web, one of said rollers being of a width to enter apertures in said web and 50 cause cessation of feed, a handle for operating said rollers, a stop to arrest feed by said rollers upon rotation sufficient to feed a predetermined length of web, a movable web aligning pin adapted to separate said 55 feed rollers upon arrest of said feed by said stop, and rotatable web gripping surfaces, one in advance and one in rear of said pin, adapted to grip said web at the side of the 60 apertures therein, one just before said rollers are separated and the other after said rollers grip the web immediately after being separated.
18. In a friction-roll manifolder employing perforated form strips, a pair of cooperative rolls for feeding said strips, a pin 65 on one roll for engaging form perforations, and means for providing form clearance between said rolls during said pin engagement.
19. In an autographic register, a pair of revoluble rolls held together under tension, 70 means for revolving them to feed duplicate strips of paper between them, and rotatable pins for positively engaging the strips of paper at the line of feed to shift them into alignment with each other for each feeding 75 operation.
20. In an autographic register, a feed roll, a yieldingly-pressed roll bearing against it for feeding duplicate strips of paper, a pair of pins on the feed roll adapted to engage 80 aligning perforations in the paper, and means for lifting the tension roll off the feed roll during the engagement of the pins with said perforations.
21. In an autographic register, a feed roll, 85 a yieldingly-pressed roll bearing against it for feeding duplicate strips of paper, a pair of pins on the feed roll adapted to engage aligning perforations in the paper, and means for lifting the tension roll off the feed 90 roll during the engagement of the pins with said perforations just before the close of each separate operation of the feed roll.
22. In a friction-roller manifolder employing perforated form strips, a drive roll 95 and a cooperative pressure roll for feeding said strips, means for relaxing the pressure between the rolls after feeding said strips a predetermined distance, and form adjusting means on said drive roll for engaging form 100 perforations at the time of said pressure relaxation.
23. In a friction-roll manifolder, a pair of revolvable rolls and means for holding them together under tension, means for revolving said rolls to feed duplicate strips of paper between them, means for separating the roll surfaces after said feeding action, and means adapted to move longitudinally of the line of feed for positively engaging 110 the paper strips to shift them into alignment with each other for each feeding operation.
24. In an autographic register, in combination, a pair of feed rolls, pressed toward each other, for feeding a plurality of superposed strips between them, and means adapted to relieve the grip of said rolls on said strips and align the strips, including a pin on one roll adapted to engage aligning 115 apertures in said strips during said relief of grip.
25. In an autographic register, in combination, a pair of feed rolls, pressed toward each other, for feeding a plurality of superposed strips between them, and means adapted to relieve the grip of said rolls on said strips just before the close of each 125 separate feed operation of said rolls and align the strips, including a pin on one roll 130

adapted to engage aligning apertures in said strips during said relief of grip.

26. In an autographic register, in combination, a pair of feed rolls, pressed toward each other, for feeding a plurality of superposed strips between them, and means adapted to move said rolls apart and align the strips including a pin on one roll adapted to engage aligning apertures in said strips while said rolls are apart.

27. In an autographic register, in combination, a pair of feed rolls, pressed toward each other, for feeding a plurality of superposed strips between them, and means, rotatable with one of said rolls, adapted to relieve the grip of said rolls on said strips and align the strips, including a pin on one roll adapted to engage aligning apertures in said strips during said relief of grip.

28. In an autographic register, in combination, a pair of feed rolls, pressed toward each other, for feeding a plurality of superposed strips between them, and means, rotatable with one of said rolls, adapted to move said rolls apart and align the strips, including a pin on one roll adapted to engage aligning apertures in said strips while said rolls are apart.

29. In an autographic register, in combination, a pair of feed rolls, pressed toward each other, for feeding a plurality of superposed strips between them, means adapted to relieve the grip of said rolls on said strips and align the strips, including a pin on one roll adapted to engage aligning apertures in said strips during said relief of grip, and a stop adapted to temporarily arrest said pin in position engaging said apertures between successive feeding operations of said rolls.

30. In an autographic register, in combination, a pair of feed rolls, pressed toward each other, for feeding a plurality of superposed strips between them, means adapted to move said rolls apart and align the strips, including a pin on one roll adapted to engage aligning apertures in said strips while said rolls are apart, and a stop adapted to temporarily arrest said pin in position engaging said apertures between successive feeding operations of said rolls.

31. In an autographic register, the combination with a roll feed element for duplicate strips provided with holes, aligning pins on the roll feed element to engage in the holes and feed the strips forward, said pins being located in a line transverse to the direction of the feed of the strips, and means

for releasing the strips from frictional feeding contact of the roll during the feeding operation of the aligning pins.

32. In an autographic register, a feed roll, a yieldingly-pressed roll bearing against it for feeding duplicate strips of paper by friction, a pair of pins on the feed roll adapted to engage aligning perforations in the paper, spaced apart lengthwise of the paper, and means for lifting the tension roll off the feed roll during the engagement of the pins with said perforations, said feed roll having a greater circumference than the spacing of the perforations.

33. In a friction-roll manifolder employing perforated form strips, a pressure roll and a cooperative drive roll having a circumference substantially equal to a form length for feeding said strips, pins on said drive roll for engaging form perforations at each revolution thereof, and means for relaxing the feeding pressure on the strips at the time of said pin engagement, said pins being idle for feeding during the greater part of a revolution of said drive roll.

34. In a friction-roll manifolder provided with form strips having holes spaced apart the length of a form, a drive roll having a circumference substantially equal to a form length and a cooperative driven roll, pins on said drive roll in normal engagement with form holes, means for effecting clearance between the rolls during the pin engagement, means for turning said drive roll a revolution of each feeding operation, and means for stripping the forms from said pins during the initial movement of said drive roll.

35. In a friction-roll manifolder provided with form strips having holes spaced apart the length of a form, a drive roll having a circumference substantially equal to a form length, means for locking and releasing said drive roll at each revolution thereof, a pressure roll cooperating with said drive roll for feeding forms nearly a form length, pins on said drive roll in engagement with form holes when said drive roll is locked, means in said drive roll for rendering the forms loosely held during said pin engagement, and a stripper adjacent said driven roll having notches for the passage of said pins.

In testimony whereof I affix my signature, in the presence of two witnesses.

LOUIS F. HAGEMANN.

Witnesses:

WILLIS B. RICE,
C. J. KULBERG.
